Designers for Obama by Visual Culture dated Nov. 7, 2008 Found on Mar. 31, 2014 at http://www.oberholtzer-creative.com/visualculture/2008/11/the-obama-brand-a-retrospective/designers_for_obama_c/.*

Primary Examiner — Robert M Spear*Assistant Examiner* — Eliza Bennett-Hattan(74) *Attorney, Agent, or Firm* — Craig A. Deutsch(57) **CLAIM**

The ornamental design for an pair of eyewear temples, as shown and described.

DESCRIPTION

FIG. 1 is a front perspective view showing the new design for an pair of eyewear temples.

FIG. 2 is a left view thereof;

FIG. 3 is a right view thereof;

FIG. 4 is a front view thereof;

FIG. 5 is a back view thereof;

FIG. 6 is a top view thereof; and,

FIG. 7 is a bottom view thereof.

The six curved lines on each of two eyeglass temples comprise the entirety of the claim. The broken lines in the drawings depict unclaimed environment and form no part of the claimed design.
